(57) **CLAIM**

The ornamental design for a front face of a vehicle wheel, as shown and described.

DESCRIPTION

FIG. 1 is a front view of a front face of a wheel showing our new design.

FIG. 2 is a top and left perspective view of the wheel shown in FIG. 1.

FIG. 3 is a front view of a front face of a wheel showing a second embodiment of our new design; and,

FIG. 4 is a top and left perspective view of the second embodiment of the wheel shown in FIG. 3.

The broken line showing of environment is for illustrative purposes only and forms no part of the claimed design.
